UNITED STATES PATENT OFFICE.

HERMAN SCHLACHT, OF NEW YORK, N. Y.

DESIGN FOR A WATCH HOLDER.

Application filed June 13, 1928. Serial No. 27,106. Term of patent 14 years.

To all whom it may concern:

Be it known that I, HERMAN SCHLACHT, a citizen of the United States, residing at New York city, in the county of New York and State of New York, have invented a new, original, and ornamental Design for a Watch Holder, of which the following is a specification, reference being had to the accompanying drawing, forming part thereof.

The figure is a perspective view of a watch holder, showing my new design.

I claim:

The ornamental design for a watch holder, as shown.

HERMAN SCHLACHT.
